Application May 31, 1941, Serial No. 101,255

To all whom it may concern:

Be it known that I, Charles E. Jones, a citizen of the United States, residing at Chicago, in the county of Cook and State of Illinois, have invented a new, original, and ornamental Design for a Guide Tab, of which the following is a specification, reference being had to the accompanying drawing, forming a part thereof.

In the drawing:

Figure 1 is a front perspective view of a guide tab showing my design.

Figure 2 is a rear perspective view of the same.

The dominant feature of the design comprises a head portion having an exposed convex front face terminating in a curvature along its side edges that is of lesser radius than the radius of the convex face, and a depending skirt portion having front and rear faces that slope generally upwardly and outwardly to merge with said rounded side edges.

I claim:

The ornamental design for a guide tab, substantially as shown and described.

CHARLES E. JONES.
